M. J. FOGARTY

NUT SHELLING MACHINE

Filed Nov. 4, 1922

Inventor

Michael J. Fogarty
By his Attorney Wm Dodge

UNITED STATES PATENT OFFICE.

MICHAEL J. FOGARTY, OF BROOKLYN, NEW YORK.

NUT-SHELLING MACHINE.

Application filed November 4, 1922. Serial No. 599,094.

To all whom it may concern:

Be it known that I, MICHAEL J. FOGARTY, citizen of the United States, and resident of Brooklyn, in the county of Kings and State of New York, have invented certain new and useful Improvements in Nut-Shelling Machines, of which the following is a specification.

The present invention relates to coconut shelling machines and the objects thereof include the provision of means for advancing the nuts; means for holding the same during their advancement against rotation; means for cutting away the shells therefrom without disturbing the meat of the nuts; means for tumbling the nuts after the shells have been thus cut away to further remove any adhering particles of shells and the dark skin covering the surface of the coco-nut meat; and also includes means for delivering the shelled coconuts.

For further comprehension of the invention, and of the objects and advantages thereof, reference is had to the following description and accompanying drawings, and to the appended claims in which the various features of the invention are more particularly pointed out.

Figure 1 of the drawings is a side elevation, partially in section, of my improved nut cracking machine. Figure 2 is a plan view of the same. Figure 3 is an end elevation of the machine, as shown from the feeding end thereof. And Figure 4 is a transverse view, partially in section, on the line 4—4, Fig. 1.

In the drawings numeral 10 designates the base of the machine, on which are carried the standards 11, 12 and 13, the latter two standards being braced together at the top by the tie plate 14. The standards 11 and 12 are provided with bearings 11^a and 12^a in which is rotatably journaled the tube or drum 15 and on which latter are fixed a driving pulley 16 and a gear 17, the latter engaging a gear 18, fixed to a stub shaft 19 journaled in a bearing 20 formed on the standard 11, which is also provided with the bearing 21 carrying one end of a shaft 22, the opposite end being supported by the bearing 23. A gear 24 is fixed to the shaft 22 and is adapted to drive the same by the pinion 25 fixed to the free end of the stub shaft 19. By means of the above gears the shaft 22 is driven by the drum 15 a correspondingly

reduced number of revolutions for rotating the face cam 26 fixed to the free end thereof.

Adjacent the face cam 26 is a rocker arm 27, pivotally mounted at its lower end by a stud 28, fixed to a hub on the foot of the bearing 23, the rocker arm being actuated by a stud and roller indicated at 29 as engaging the groove in the face cam 26. At its upper end the rocker arm 27 engages projecting lugs 30, formed on the slide head 31, the foot of which slidably engages the rail 32 fixed to the ledge 33 of the standard 13. Through the foot of the head 31 extends a slot adapted to receive and permit the movement of the arm 27, a corresponding slot being provided in the rail 32. To the head 31 is fixed a feed plunger 34, having an enlarged free end shaped to engage an end of the coconuts, the latter shown at several points in the machine by the dotted lines 35. The plunger is movable within the feed box, indicated by the side plates 36, and the outward movement of the plunger is sufficient to permit the manual introduction of the nuts one at a time into the feed box, as shown in Fig. 2, the full movement of the plunger corresponding to that of the upper end of the rocker arm 27, as represented by the dotted lines 37 and effected by the face cam 26.

To hold the nuts against rotation during their advancement by the feed plunger, a series of gripper wheels 38 having penetrable gripping faces are mounted to freely rotate in blocks 39, the latter being slidable in the gripper frame 40, fixed upon the standard 13. These slide blocks 39 are lengthwise provided with chambers or recesses arranged to receive helical compression springs 41 normally acting to urge the gripper wheels in a resilient manner into engagement with the shell of the nuts with sufficient tension to prevent their rotation, but allowing them to be advanced by the pressure of the feed plunger. As the nuts pass between the gripper wheels they are also advanced between a series of cutting wheels 42, fixed to the free ends of the shafts 43, the latter being supported adjacent the cutters by the bearings 44, pivotally carried by the fork-shaped slide blocks 45, slidable in the cutter frame 46, the latter being fixed to the free end of the drum 15. The slide blocks 45 are provided with longitudinally extending chambers or re-

cesses in which are mounted helical compression springs 47 which yieldingly urge the cutting wheels 42 against the shell of the nuts, the cutting depth thereof being limited by the hubs formed on the side faces of the wheels and which engage the shell and form a stop for the cutting action.

For the rotation of the cutting wheels, the standard 12 is fixedly provided with a gear 48 having internal teeth, engaged by a series of pinions 49 corresponding in number with the cutting wheels, the pinions being fixed upon stub shafts 50, which are mounted at opposite sides of the pinions in bearings 51, formed on the gear hub 52, fixed upon the drum 15. These stub shafts at one end project beyond their bearings and have fixed thereon one of the members 53 of universal joints, the opposite joint members 54 being fixed to the driving ends of the shafts 43, the universal joint members being pivoted together in the usual manner for transmitting angular driving movement to the shafts for the continual rotation of the cutting wheels 42 in their resilient radial movement. Thus it will be obvious that during the rotation of the drum 15 by the pulley 16, the rotation of the pinions 49 will be effected by their engagement with the fixed internal gear 48, and a double rotation of the several cutters will result, one about the nut in one direction and one in the opposite direction about their own axes, and during the advancement of a nut, separated spiral grooves will be cut in the shell, the spacing of such grooves depending upon the variation in alinement of the cutting edges of the wheels with respect to one another, as indicated in Fig. 2.

To secure the desired cutting action upon the nut-shells, the latter are maintained in a substantially centralized position with respect to the tube or drum 15. As herein shown this position is effected by means of the guide-blocks 55 and 56 respectively provided in the feed box 36 adjacent the gripper wheels 38 and in the drum 15 adjacent the cutting wheel 42, the blocks being resiliently mounted in their respective positions by the springs 57 disposed in suitable recesses and by connection pins 58. In action the blocks serve to adapt themselves to variable sizes of nuts and to furthermore act as a support for the latter in connection with the operation of the cutting and the gripping wheels.

As shown in Fig. 1, sections of the drum 15 are cut away, as indicated at 59, to afford a clearance for the cutter parts in their action upon the smaller or end portions of the shell of the nuts. To provide the necessary tumbling and scouring action upon the shelled nuts as carried along from the cutter, the interior surface of the drum 15 is fitted with projecting knobs 60 arranged to

assist the advancing movement of the nuts therethrough as essentially effected by the feed plunger 34. At the delivery end of the drum an elbow 61 is indicated, whereby the nuts may be directed downwardly or led away in any desired direction or manner.

In the operation of the machine the nuts are manually fed one at a time into the feed box 36 and from there advanced by the plunger 34 between the series of resilient guide blocks 55, and the resilient gripper wheels 38, the tapering ends of the nuts serving in their advancement to automatically spread the resilient parts and effect a centralized position of the nuts and a gripping action thereon to prevent rotation thereof as they are advanced to the closely adjacent resilient cutting wheels 42, which latter are likewise automatically spread apart or closed to accommodate the varying diameter of the work during its advancement, and cut into the shells thereof spaced spiral grooves substantially the full length of the nuts, the angular relation of the grooves to the axis of the nut serving in a measure to remove the shell sections as rapidly as they may be cut.

While I have shown and described the preferred construction and arrangement of the several parts of the invention it is to be understood that various detail changes may be made therein to suit the variable situations without departing from the essential principles or scope of the invention.

What I claim as my invention and desire to secure by Letters Patent, is:

1. A coconut shelling machine comprising means for advancing a nut, a shell cutter, a gripper device operable by the advance of the nut to hold the same against rotation, and means for automatically delivering and tumbling the nuts from said shell cutter.

2. A coconut shelling machine comprising means for advancing a nut, a gripping device arranged to hold the nut against rotation, a rotary shell cutter adapted to yieldingly engage the nut, means for jointly rotating the cutter about its own axis and about the axis of the nut during the latter's advancement, and means for delivering the nut from said shell cutter.

3. A coconut shelling machine comprising means for advancing a nut, a gripping device arranged to hold the nut against rotation during said advancement, a plurality of rotary cutters adapted to yieldingly engage the nut, and means for rotating said cutters around the nut during the advancement thereof, said cutters being longitudinally disposed apart with respect to one another to effect a relative spacing of the grooves cut in the shells of the nut.

4. A coconut shelling machine comprising means for advancing a nut, a gripping device arranged to hold the nut against rotation during said advancement, a shell cutter,

and a drum disposed to receive and guide the nut from said shell cutter.

5. A coconut shelling machine comprising means for advancing a nut, a gripping device arranged to hold the nut against rotation during said advancement, a shell cutter, and a rotating drum disposed to receive and guide the nut from said shell cutter.

6. A coconut shelling machine comprising 10 means for advancing a nut, a gripping device arranged to hold the nut against rotation during said advancement, a shell cutter, and a rotating drum disposed to receive, guide and tumble the nuts from said shell cutter.

15 7. A coconut shelling machine comprising means for advancing a nut, a gripping device arranged to hold the nut against rotation during said advancement, a shell cutter, and a rotating drum arranged to receive, guide, tumble and deliver the nuts from said shell cutter.

20 8. A coconut shelling machine comprising means for advancing a nut, a fixed frame, 25 gripper blocks slidable in said frame, gripper wheels rotatable in said blocks and disposed to be engaged and rotated by the nut in the advancement thereof, and resilient means acting through said blocks to effect a 30 yielding tension between said gripper wheels and nut to hold the latter against rotation.

9. A coconut shelling machine comprising 35 means for centralizing and advancing a nut, and a gripping device arranged to engage and hold said nut against rotation, the said gripping device consisting of a series of rollers rotatable on axes relatively fixed with respect to the advancement of the nut.

10. A coconut shelling machine comprising 40 means for advancing a nut, and a gripping device arranged to engage and hold said nut against rotation, the said gripping device consisting of a series of rollers rotatable about axes relatively fixed with respect 45 to the advancement of the nut.

11. A coconut shelling machine comprising 50 means for advancing a nut, a gripping device including a series of rollers arranged to engage and hold the nut against rotation, said rollers being rotatable about axes relatively fixed with respect to the advancement of the nut, and yielding means arranged to urge said rollers toward the nut.

12. A coconut shelling machine comprising 55 means for advancing a nut, a gripping device including a series of rollers arranged to engage and hold the nut against rotation, said rollers being resiliently mounted for movement toward the nut but immovable with respect to the advancement thereof.

13. In a coconut shelling machine, a feed 60 box, guide-blocks therein arranged to centralize a nut, a feed-plunger mounted within said box and adapted to advance the nut between said guide-blocks, and a gripper de-

vice arranged to engage and hold the nut against rotation during such advancement.

14. In a coconut shelling machine, a rotating member, a gear frame and a cutter frame fixed to said rotating member, a pinion gear journaled in said gear frame and having a driving end projecting therefrom, a fixed gear engaged by said pinion gear, a block slidable in said cutter frame and having a bearing pivotally mounted thereto, a shaft having a cutter fixed at one end thereof and journaled adjacent the cutter in the pivotally mounted bearing, and a universal joint connection between the opposite end of said cutter shaft and the driving end of 80 said pinion gear.

15. In a coconut shelling machine, a rotating drum, a cutter frame fixed to said drum, a cutter carried by said frame, and means operated by the rotation of said drum 85 for rotating said cutter about its own axis.

16. In a coconut shelling machine, a rotating drum, a cutter frame fixed to said drum, a cutter mounted in said frame for movement toward and from the center of said drum, and means operated by the rotation of 90 said drum to rotate said cutter about its own axis.

17. In a coconut shelling machine, a rotating drum, a cutter frame fixed to said drum, 95 a cutter slidably mounted in said frame for radial movement with respect to said drum, resilient means normally urging said cutter toward the center of said drum, and means operated by the rotation of the latter for rotating said cutter about its own axis.

18. In a coconut shelling machine, a standard provided with a bearing, a drum rotatable in said bearing, a gear fixed to said standard co-axially with said drum, a gear frame fixed to said drum, a pinion gear engaging said fixed gear and journaled in said gear frame and having a driving end projecting therefrom, a cutter frame fixed to 105 said drum, a pivotally mounted bearing radially slidable in said cutter frame, a cutter shaft mounted at one end in said pivoted bearing and connected at its opposite end by a universal joint to the driving end of said pinion gear, and a cutter fixed to said shaft.

110 19. In a coconut shelling machine, a standard provided with a bearing, a drum rotatable in said bearing, a gear fixed to said standard co-axially with said drum, a gear frame fixed to said drum, a series of pinion gears engaging said fixed gear and journaled in said gear frame and having driving ends projecting therefrom, a cutter frame fixed to said drum, pivotally mounted bearings radially slidable in said cutter frame, cutter shafts mounted at one end in said pivoted bearings and connected at their opposite ends by universal joints to the driving ends of said pinion gears, cutters fixed to 115 said shafts adjacent said pivoted bearings, 120 125

and resilient means adapted to normally urge said cutters toward the axis of said drum.

20. In a coconut shelling machine, means for advancing the nuts and cutting the shells therefrom, and a rotating drum disposed to receive and tumble the nuts from said cutting means.

21. In a coconut shelling machine, means for advancing the nuts and cutting the shells therefrom, and a rotating drum disposed to receive, tumble and deliver the nuts from said cutting means.

22. In a coconut shelling machine, means for advancing the nuts and cutting the shells therefrom, and a rotating drum disposed to receive and centralize the nuts during the cutting action.

23. In a coconut shelling machine, gripping devices for holding the nuts against rotation, shell cutting devices, tumbling devices, and a feed plunger arranged to advance the nuts through said gripping, cutting, and tumbling devices.

24. In a coconut shelling machine, gripping devices for holding the nuts against rotation, shell cutting devices, combined tumbling and delivering devices, and a feed plunger arranged to advance the nuts

through said gripping, cutting, and combined tumbling and delivering devices. 30

25. In a nut shelling machine, means for advancing the nuts, and a shell cutting device comprising a rotatable cutter, and means for jointly rotating the cutter about its own 35 axis and about the axes of the nuts during their advancement.

26. In a nut shelling machine, means for advancing a nut, means for holding the nut against rotation during such advancement, a 40 series of rotatable shell cutters adapted to engage the nut, and means for jointly rotating said cutters about their own axes and about the axis of the nut during the advancement of the latter. 45

27. In a nut shelling machine, means for advancing a nut, means for holding the nut against rotation during such advancement, a series of rotatable shell cutters adapted to engage the nut, and means for jointly rotating said cutters about their own axes in one direction and about the axis of the nut in the opposite direction during the advancement of said nut. 50

Signed at Brooklyn, in the county of 55 Kings and State of New York, this first day of November, A. D. 1922.

MICHAEL J. FOGARTY.
